UNITED STATES PATENT OFFICE.

ORVILLE J. PRICE, OF CHICO, CALIFORNIA.

COMBINATION CARBON-CLEANER.

1,299,609.

Specification of Letters Patent. Patented Apr. 8, 1919.

Application filed January 9, 1918. Serial No. 211,091.

To all whom it may concern:

Be it known that I, ORVILLE J. PRICE, a citizen of the United States, residing at Chico, in the county of Butte, State of California, have invented certain new and useful Improvements in Combination Carbon-Cleaners; and I do declare the following to be a clear, full, and exact description of the same, reference being had to the accompanying drawings, and to the characters of reference marked thereon, which form a part of this application.

This invention relates to improvements in paraphernalia used in connection with internal combustion engines, particularly that type used in motor vehicles. The object of the invention is to produce a combination structure which will be utilized to both keep the engine comparatively free of carbon deposits and at the same time aid in attaining perfect combustion of the fuel within the engine and thus materially lessen the possibility of carbon being deposited therein.

A further object of the invention is to maintain a continuous cleansing action within the engine cylinders whenever the engine is in operation and in addition to this provide a means whereby a thorough cleansing of the engine of all carbon deposits may be had at predetermined times. The same mechanism may also be used for priming the engine for starting purposes, or for accelerating the speed or for controlling the grade of explosive mixture admitted to the engine. All of these things go to both enhance the efficiency of the engine and at the same time keep it free and clear of carbon which is always a disturbing element.

A still further object of the invention is to produce a simple and inexpensive device and yet one which will be exceedingly effective for the purpose for which it is designed.

These objects, I accomplish by means of such structure and relative arrangement of the parts as will fully appear by a perusal of the following specification and claims.

On the drawings, similar characters of reference indicate corresponding parts in the several views.

Figure 1 is a perspective view of an engine of a motor vehicle showing how my improved apparatus may be attached thereto.

Fig. 2 is a vertical section through the fluid container used in connection with the apparatus.

Fig. 3 is a sectional view taken on a line X—X of Fig. 1.

In order that the following detailed description of the invention may be more readily understood, I wish to point out that it is a well known fact that kerosene and water separately have heretofore been used for cleansing carbon from engines. This has been done in various ways either by the admission of the same into the engine through the carburetor while the engine is running and in a heated condition, or the kerosene has been admitted to the engine through the pet-cocks or other openings and allowed to remain within the cylinders for a considerable length of time. This softens the carbon and upon the engine being started it is discharged through the exhaust manifold. By my present invention, I aim to introduce into the engine cylinders a vaporized kerosene properly proportioned to soften and cleanse any carbon deposits within such cylinders. This mixture is continuously admitted when the engine is operating under its own power. Thus, in addition to serving as a carbon remover, it acts to generally increase the efficiency of the combustion within the cylinders as it is a well known fact that a vaporized kerosene, when mixed with the explosive mixture in proper proportions, tends to increase the combustible properties of such mixture. While this vaporized kerosene is admitted continuously during the operation of the motor, I also provide a further means whereby a considerable quantity of kerosene and water may be admitted at any desired time to the engine and thus give it a thorough and complete cleansing at given periods. In connection with the admission of the vaporized kerosene, I may also increase the quantity of air admitted to the cylinders when the engine is in operation. This is a very advantageous feature especially when the motor is being operated in varying temperatures or altitudes.

Lastly, I may disconnect the kerosene and water support and admit raw gas directly to the intake manifold of the engine for priming purposes.

Referring now more particularly to the characters of reference on the drawings, the numeral 1 designates the intake manifold of the engine and 2 the exhaust manifold thereof.

105

117

The numeral 3 designates a receptacle of any desired or preferred form connected adjacent the exhaust manifold.

In practice, I fill this receptacle 3 with 5 suitably proportioned quantities of kerosene and water. At one end of the receptacle 3 is an outlet valve 4 connected by a pipe 5 with a T 6, the lateral extension 7 of which is in communication with the interior of the in-

10 take manifold 1.

An elbow 8 communicates with the upper side of the receptacle 3 and is connected with a pipe 9 extending parallel with the said receptacle 3. The lower inner side of this 15 pipe 9 is in a lower plane than the point of communication from the elbow 8 into such pipe, as shown clearly in Fig. 3, so if any raw liquid should flow down through the said pipe 9 it will not discharge into the receptacle 3 but will carry on down through 20 the said pipe 9, which communicates at its lower end with the T 6.

The opposite end of the pipe 9 is in connection with a cross fitting 10. The said 25 fitting 10 is placed in communication at its upper end by means of ports 11 and 12 with outlet pipes 13 and 14 projecting through the fluid containing receptacle 15. This receptacle 15 is divided by a center division 30 wall 16 into two compartments 17 and 18.

A filling funnel 19 is provided for the compartment 17 and a filling funnel 20 is provided for the compartment 18. Each of the compartments 17 and 18 is provided 35 with a small bleed port 17^a and 18^a, respectively, to prevent a tendency to vacuum within the compartments. A port 17^b leads from the compartment 17 into the pipe 14 and a port 18^b leads from the compartment

40 18 into the pipe 13. The open or closed position of the port 17^b is controlled by a valve stem 21 threaded into the pipe 14, as at 22, and provided with a thumb screw 23 at its upper end, held against abnormal rotation by means of any desired tension spring 24.

Similarly, the open or closed position 45 of the port 18^b is controlled by a valve stem 25 threaded into the pipe 13, as at 26, and provided at its outer end with a thumb screw 27 likewise held against abnormal rotation by means of a tension spring 28. A manually controlled air inlet valve 29 communicates with the fitting 10 on one side and a semi-manually controlled air inlet valve 30 55 communicates with the fitting 10 from the opposite side. This valve 30 may be of that type shown in Patent No. 1,026,533 and commonly known as the "Stewart gas saver." When this type is used, the flexible wire 31

60 may be extended along the steering post 32 to a point adjacent the steering wheel 33 where it may be controlled by the usual finger lever 34. The purpose and action of these air valves will be set forth hereafter.

65 In practice, the compartment 17 may be

filled with kerosene and the compartment 18 with gasoline. As has already been noted, the receptacle 3 is filled with kerosene and water. The air valve 29 may be set at any desired position to permit a suction from the 70 manifold intake 1 through the T 6 and pipe 9. As the engine operates, the heat from the exhaust manifold 2 heats the fluids within the receptacle 3. This causes a vapor of kerosene and water to rise from said receptacle and pass into the elbow 8 and hence 75 into the pipe 9, whereupon it may be drawn into the intake manifold 1 and hence into the engine. This vapor will both tend to perfect the combustion of the fuel and at the same time will soften and loosen any carbon 80 deposits which tend to form within the engine cylinders.

This action will be continuous whenever the engine is in operation and the beneficial 85 results will therefore be ever present within the engine cylinders.

If at any predetermined time it is desired to admit greater quantities of kerosene or water directly to the engine cylinders, the 90 valve 4 may be opened and then the suction of the engine will draw a quantity of the kerosene or water directly into the engine through the pipe 5, depending on the level 95 of the dividing line of the two fluids in the receptacle with respect to the opening in the valve 4. It has been found in practice that the use of either kerosene or water is beneficial for cleaning the cylinders of the engine when warm and running.

If it is desired to give the engine cylinders a thorough cleansing with kerosene alone, the valve 21 is opened and the kerosene will then flow through the port 17^b and port 12 into the fitting 10, thence through the pipe 9 and T 6 into the intake manifold 1. From here it will be drawn from the suction of the engine directly into the engine cylinders. The advantage of this will be obvious to those skilled in the art. For priming purposes, the compartment 18 may be placed in communication with the engine by opening the valve 25. Gasoline from this compartment 18 will then be admitted through the port 18^b, pipe 13, port 11, fitting 10, pipe 9 and T 6 into the intake manifold 1. The suction of the engine will then draw this into the engine cylinders. This can be used for priming the engine or enriching the explosive mixture at any time found desirable.

The fact that the bottom lever of the pipe 9 is below the connection of the elbow 8 therewith will prevent any of this raw kerosene or gasoline from flowing into the receptacle 3 as it is passing through the pipe 9.

A quantity of air may be admitted through the valve 29, and this quantity may be increased or diminished as desired during the 130

operation of the engine by means of the valve 30. This air regulation is necessary to properly provide for the admission of the cleansing solution or vapor and at the same time it may be utilized for regulating the amount of air in the explosive mixture within the engine cylinders to produce the greatest efficiency of the engine.

It will be seen from the foregoing description that I have produced a combination device which is capable of the following functions, namely: first, continuous cleansing of the carbon from the engine; second, the thorough cleansing of the carbon from the engine cylinders at predetermined times; third, priming of the engine quickly and easily at any desired moment; fourth, an air control which may be brought into play at any desired time. The many advantages of all of these will be readily apparent to those skilled in the art. In addition to those advantages which will be apparent, I have also found from actual experience that by the use of my improved apparatus, I am able to reduce the normal fuel consumption of the engine from ten to twenty-five per cent. and in addition to this to increase the speed of the motor vehicle from three to five miles for each fifteen miles of the present normal speed.

It will also be seen, from the foregoing description, that I have produced such a de-

vice as substantially fulfills the objects of the invention as set forth herein.

While this specification sets forth in detail the present and preferred construction of the device, still in practice, such deviations from such detail may be resorted to as do not form a departure from the spirit of the invention.

Having thus described my invention, what I claim as new and useful and desire to secure by Letters Patent is:—

A carbon cleanser for engines comprising a receptacle adapted to hold a cleansing fluid arranged to be heated to pass off a vapor, an outlet from the receptacle adapted to be placed in communication with the engine to admit the vapor thereto, and means for admitting other fluids to the engine through said outlet, such means comprising a receptacle having a plurality of compartments for containing the fluids, and a single outlet communicating with the outlet from the first named receptacle, and valves controlling communication between the compartments and the second named outlet.

In testimony whereof I affix my signature in presence of two witnesses.
